STRAIN YOKE FOR ELECTRICAL CONDUCTORS

John J. Taylor, Barberton, Ohio, assignor to The Ohio Brass Company, Mansfield, Ohio, a corporation of New Jersey

Application August 1, 1934, Serial No. 737,964

5 Claims. (Cl. 173—251)

This invention relates to a cross yoke for a strain member by means of which a pair of insulator strings may be connected to an electrical conductor or to a supporting structure. The yokes are usually used in pairs, the ends of the yokes being connected by insulator strings and the central portion of the yoke being connected to the transmission line and the supporting structure respectively.

10 One object of the invention is to provide a close coupled yoke so as to reduce the effect of vibration and also to conserve space.

Another object of the invention is to provide a strong and mechanically efficient device which 15 shall be economical to manufacture and easy to install.

A further object of the invention is to provide a device of the class named which shall be of improved construction and operation.

20 Other objects and advantages will appear from the following description.

The invention is exemplified by the combination and arrangement of parts shown in the accompanying drawing and described in the following specification, and it is more particularly pointed out in the appended claims.

In the drawing:

Fig. 1 is a plan view showing one embodiment of the present invention.

30 Fig. 2 is an elevation of the device shown in Fig. 1.

Fig. 3 is an end view of the device shown in Figs. 1 and 2.

Fig. 4 is a central transverse section of a modified form of the invention.

As shown in the drawing, the strain yoke is made up of a pair of complementary bars 10 and 11 which are held together in spaced relation by connecting bolts 12; the bars may be spaced apart by any suitable means such as webs 13 and bosses 14. The yoke is provided with a central pivot pin 15 for attachment to the supporting structure or to the strain clamp for holding the conductor. End pivots 16 and 17 are also provided for attachment to the insulator strings. It is desirable that the pivotal axes 15, 16 and 17 be as nearly in a common plane as practical in order to prevent vibration of the yoke about an axis extending longitudinally of the yoke. If 50 the pivots 15, 16 and 17 were arranged in a triangle having a considerable altitude, there would be danger that vibration of the conductor would set up vibration of the yoke about an axis transverse to the conductor and extending in the plane 55 of the triangle formed by the pivots 15, 16 and 17

and somewhere between the base and the apex of the triangle. This danger is avoided by keeping the axes of the pivots in as nearly a common plane as possible. In order to do this, the side bars or plates 10 and 11 are spaced apart to form the 5 yoke and transversely perforated at a point approximately midway between their edges for receiving the pivot pin 15. A U-shaped bar or clevis 18 engages the pivot pin 15 and is provided with a transverse pivot pin 19 for attachment to 10 the support or to the conductor. This double pivot arrangement provides a universal joint between the yoke and the conductor or support so that the conductor is free to assume any angular position it may tend to take relative to 15 the yoke. This reduces the effects of vibration and also prevents undue stress in the yoke in case one of the insulator strings connected to the pivots 16 and 17 should break.

A closer coupling and a somewhat more nearly 20 universal pivotal arrangement is secured by the modified form of central pivot member shown in Fig. 4. In this modification, a central pivot block 20 is provided having laterally extending pintles 21 for engaging the openings in the side bars 10 25 and 11 of the yoke. The block 20 has a central rectangular recess for receiving the end of a link or other attachment member by means of which the yoke is connected to the supporting structure or to the strain clamp for the conductor. 30 The sides of the block are perforated at 22 for receiving the pivot pin 19 but in this case, it will be noted that the axis of the pivot pin 19 is in the same plane as the axis of the pintles 21, that is, the axis of the pin 19 and the pintles 21 35 intersect each other.

The side bars 10 and 11 are preferably bent inwardly at their ends to engage each other and thus form additional spacing abutments for holding the bars in spaced relation to each other. 40 The abutting ends of the bars may be extended, as shown at 23 and 24, and provided with holes 25 for the attachment of arcing members. The extensions 23 and 24 are not, however, an essential feature of the invention. 45

It will be seen that the invention provides a strong, closely coupled yoke and one having a pivotal connection at the center of the yoke for the supporting structure or conductor which permits substantially universal pivotal movement to 50 reduce the effect of vibration.

I claim:

1. A strain yoke comprising spaced side members having aligned transverse openings therein at the middle of said yoke, means for connect-

- ing said members together, side by side but spaced apart at their middle, connecting means at the opposite ends of said yoke, and pivotal connecting means at the middle of said yoke for holding a connected member thereto, said pivotal connecting means comprising a pivot block and oppositely directed trunnion portions extending into the aligned openings in said side members and pivotally securing said block between said plates, said block having a pivotal opening therethrough transverse to the axis of said trunnion portions and in position to receive a pivot pin disposed between said side members with its axis extending longitudinally of said yoke, said block, pivot pin and trunnion portions providing for pivotal movement between said yoke and connected member about an axis transverse to said yoke and also about an axis extending longitudinally of said yoke.
2. A strain yoke comprising a lever arm, connections at the opposite ends of said arm and a central connection comprising a block having pivotal connection with said arm and having a pivot for connecting a strain member to said arm, the axis of the pivotal connection of said block with said arm and the axis of the pivot for connecting a strain member to said arm intersecting each other, the common plane of said intersecting axes lying between opposite longitudinally extending boundary edges of said lever arm.
3. A strain yoke comprising a lever arm having sides spaced apart at their middle portion, means for connecting strain members to the ends of said yoke respectively, and a pivot block interposed between said sides at the middle of said yoke, said pivot block having pintles thereon en-

gaging openings in the sides of said yoke and having a perforation therethrough transverse to the axis of said pintles for receiving a pivot pin for connection to a central strain member.

4. A strain yoke for an electrical transmission line comprising a pair of plates having portions thereof spaced apart and arranged side by side, pivot pins disposed transversely of said plates at the opposite ends of said yoke for supporting insulator strings to be connected to said pivot pins respectively, a pivot block disposed between said plates at the center of said yoke and having pintles thereon pivotally connected with said plates, said block having a recess therein for receiving a connector and a pivot pin for said connector extending through said block and adapted to extend through said connector transversely of said pintles and having its axis intersecting the axis of said pintles.

5. A yoke for supporting an electrical conductor comprising a pair of plates disposed side by side but spaced apart at their middle, means for securing said plates in spaced relation to form a yoke, pivot pins disposed transversely of said plates at the opposite ends of said yoke for connection to insulator strings, a pivot block disposed between said plates at the middle of said yoke, said pivot block having pintles thereon journaled in said plates, said block having a recess therein for receiving a strain member, and a pivot pin for securing said strain member to said block, said pivot pin having its axis transverse to the axis of said pintles and substantially intersecting the axis of said pintles.

JOHN J. TAYLOR. 35
